(57) **CLAIM**

The ornamental design for a bottle lid, as shown and described.

DESCRIPTION

FIG. 1 is a front, top perspective view of a bottle lid, showing my new design;

FIG. 2 is a front, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view of the bottle lid, shown in a position of use;

FIG. 10 is another perspective view of the bottle lid, shown in an alternative position; and,

FIG. 11 is another perspective view of the bottle lid, shown in an alternative position.

The evenly dashed lines are shown for the purpose of illustrating both parts of the bottle lid as well as environmental subject matter. None of the dashed lines form part of the claimed design.

1 Claim, 11 Drawing Sheets
